UNITED STATES PATENT OFFICE.

THEODORE NAGEL, OF CHICAGO, ILLINOIS, ASSIGNOR TO THE NAGEL-CHASE MFG. CO., OF CHICAGO, ILLINOIS, A CORPORATION OF ILLINOIS.

VAPOR BURNER.

Application filed December 7, 1925. Serial No. 73,756.

This invention relates to certain improvements in a vapor burner, designed primarily for illuminating purposes, and refers more particularly to burners of the kind which 5 use a volatile liquid fuel the vapors of which are combustible, when united with air in proper amount, to produce a flame of intense heat.

The present improvements include means 10 by which the burner may be readily pre-heated with a small flame, as from a match, whereby to promote vaporization of the fuel preliminary to lighting of the burner. This and other objects of my invention, which 15 will more fully hereinafter appear, are set forth in the accompanying description and drawings wherein I have illustrated a preferred embodiment thereof in the manner following:

20 Figure 1 is a view in elevation of a lamp equipped with the present burner with the shade therefor appearing in section;

Fig. 2 is an enlarged transverse section on line 2—2 of Fig. 1; and

25 Fig. 3 is a detail in vertical section, taken on line 3—3 of Fig. 4.

I would have it understood that the improved features herein set forth are applicable generally to vapor burners, without 30 special regard to the particular lamp or lantern structure with which they are incorporated. For purposes of exemplification, a lamp such as is shown in Fig. 1 may conveniently be referred to. It comprises a 35 hollow base 10 constituting a font for the reception of a volatile liquid fuel such, for example, as gasoline or kerosene. It may be provided, as is usual, with a plug 11 which provides a closure for the filling opening.

40 Extending upwardly from the font is a tube 12 which, if desired, may be surrounded by a handle 13 by which the entire lamp may be conveniently moved about.

45 Connected to the upper end of the tube 12 is a T-fitting 15 having therein a needle valve which includes a screw stem 16 operable by a knurled wheel 17. A generating tube 24 which extends upwardly from the fitting is connected thereto in any suitable 50 manner as by a coupling nut 25.

At its upper end the generating tube communicates with a mixing chamber 30 with which connects a depending air pipe 31 the lower end of which is secured to a base plate 55 32 laterally extending from the fitting 15.

By this means the air pipe serves as a support for the burner and the several parts which are carried thereby. Included in the burner structure is an upwardly extending pipe 33 which connects with a manifold 34 from which leads downwardly a pair of depending tubes 35 each adapted to support at its lower extremity an incandescent mantle 36. To complete the illustrative lamp structure, a head 37 supported on the manifold 34 serves as a mounting whereon to carry a shade 38. Such structural details, however, form no part of my invention, but are merely shown as appropriate to complete the lamp which is illustrated in Fig. 1.

Carried by the generator tube at a desired point between its ends, is a flue 40 of special formation. As shown, it consists of sheet metal, preferably copper, or a copper alloy, having incisions which permit certain portions thereof to be inwardly bent in the form of straps 41. The remaining proximate portions constitute outer straps 42 (see Fig. 3). Elsewhere the flue walls are bent around as at 43 to embrace the generating tube upon opposite sides thereof. As shown, the embracing edges of the flue approach each other closely upon the rear side of the generating tube. The space intervening between these edges may be filled, as at 44, with a solder of silver. The flue is adhered to the generating tube preferably by brazing, so as to obtain a maximum heat conducting connection therewith.

At the time the present burner is to be 90 started, the flame of a match, or other small combustible article, may be applied to the one side of the generating tube just below the flue thereon. The flame will impinge against the lower edges of the inner and outer straps 41 and 42; it will also come in contact with the generating tube behind the inner straps 41, but not elsewhere. The heat so applied to the strap edges will be conducted quickly by these straps to the two 95 sides and rear portion of the generating tube, whereby the entire tube periphery will be heated at once. The result of this is to raise the temperature within the tube in a short space of time sufficiently to promote 100 vaporization of the fuel whereby the burner may be readily ignited.

I would have it noted that the flue just described is of advantage in that it permits 105 a flame to impinge directly against one side 110

of the generating tube; at the same time a considerable extent of flue edge surface is impinged by the flame so as to transfer heat through the conducting walls of the flue to the generating tube upon the sides and rear portion thereof. The solder between the two heating edges of the flue conducts this heat across the gap whereby the heat is circumferentially distributed.

10 It is manifest, of course, that the exact form and shape of this flue may be modified in various ways, but inasmuch as a match flame may be applied to the generating tube only upon one side thereof, the illustrative structure is typical of one embodiment which will very satisfactorily perform the intended purposes of this invention.

I claim:

20 1. The combination with a vapor burner having a generating tube in connection with a fuel supply source, of heat conducting means affixed to the tube comprising a flue of sheet metal having superimposed straps arranged edge to edge in double rows upon one side of the tube in spaced relation thereto and to each other, the straps being extended from walls which are bent around to embrace the tube upon the opposite and rear sides thereof whereby to deliver thereto heat resulting from impingement of a flame upon the strap edges, the disposition of the straps relative to the front side of the tube being such that a portion of the flame may also contact therewith when impinging upon the flue straps, substantially as described.

25 2. The combination with a vapor burner having a generating tube in connection with a source of fuel supply, of a flue attached to the tube at a point intermediate its ends, the flue being formed with separated edges adapted to be impinged by a small flame which may also impinge upon one side of the tube, the several edged portions of the flue being united to heat conducting walls which embrace the tube upon the side and far por-

tions thereof in a manner to distribute heat peripherally to the tube, substantially as described.

3. In a vapor burner, the combination with a generating tube in connection with a fuel supply source, of a flue having a brazed connection with the tube and comprising a sheet metal structure embracing the tube upon opposite sides thereof, the flue being extended upon one tube side to provide straps disposed in general alignment with the tube and each separated from the others, all of the straps being so disposed relative to the tube that a small flame may impinge simultaneously upon the lower edges of the several straps and also upon the proximate side of the tube, substantially as described.

4. In a vapor burner, the combination with a generating tube, in connection with a source of fuel supply, of a flue secured to the tube upon opposite sides and the far side thereof, the flue being formed of sheet metal which is extended around the near side of the flue to provide inner and outer straps separated from each other and from the tube such that a small flame when in contact with the near side of the tube will also impinge upon the several straps to cause heat to be conducted by the flue to the sides and rear portions of the tube, substantially as described.

5. In a vapor burner, the combination with a generating tube in connection with a source of fuel supply, of means for conducting heat applied to one side of the tube to the sides and far portions thereof, said means comprising a flue having a heat conducting connection with such portions of the flue and extended around upon the near side thereof to present a plurality of separated edges against which a match flame may impinge when also impinging against the tube, substantially as described.

THEODORE NAGEL.
